DESCRIPTION

FIG. 1 is a perspective view of a first embodiment of a
package according to the present invention;

FIG. 2 is a front view of the package of FIG. 1;

FIG. 3 is a back view of the package of FIG. 1;

FIG. 4 is a first side view of the package of FIG. 1;

FIG. 5 is a second side view of the package of FIG. 1;

FIG. 6 is a top view of the package of FIG. 1;

FIG. 7 is a bottom view of the package of FIG. 1;

FIG. 8 is a perspective view of a second embodiment of a
package according to the present invention;

FIG. 9 is a front view of the package of FIG. 8;

FIG. 10 is a back view of the package of FIG. 8;

FIG. 11 is a first side view of the package of FIG. 8;

FIG. 12 is a second side view of the package of FIG. 8;

FIG. 13 is a top view of the package of FIG. 8; and,

FIG. 14 is a bottom view of the package of FIG. 8.

The portions of the drawings shown in broken lines are
illustrated for the purpose of showing the environment of the
package and form no part of the claimed design. Additionally,
the stippling in the drawings represents a contrast in
appearance from non-stippled areas.
